UNITED STATES PATENT OFFICE.

JOSEPH OVILA MONTREUIL, OF QUEBEC, QUEBEC, CANADA.

CONDUIT.

Application filed November 15, 1921. Serial No. 515,846.

To all whom it may concern:

Be it known that I, JOSEPH OVILA MONTREUIL, a subject of the King of Great Britain, and a resident of Quebec, in the Province of Quebec and Dominion of Canada, have invented a new and Improved Conduit, of which the following is a full, clear, and exact description.

This invention relates to improvements 10 in conduits, particularly to that form of conduit ordinarily used as a drain or culvert pipe.

An object of the invention is to provide a conduit which will be light in weight, compact to transport, and unlikely to break during transportation, easy to assemble, simple and practical in construction, strong, durable and efficient in use, and comparatively inexpensive to manufacture.

20 With these and other objects in view, the invention consists in certain novel features of construction and combinations and arrangements of parts as will be more fully hereinafter described and pointed out in 25 the claims.

In the accompanying drawings:

Figure 1 is a perspective view showing several sections of my improved conduit assembled;

30 Figure 2 is an enlarged view in section on the line 2—2 of Figure 1;

Figure 3 is a similar view on the line 3—3 of Figure 1; and

35 Figure 4 is a reduced end view showing the compact manner in which the slabs forming the conduit sections may be packed for shipment.

My improved conduit is triangular in cross section and comprises a plurality of 40 interlocking sections, each section including a plurality of interlocking slabs.

Referring more specifically to the drawings, I have used the reference numeral 1 to designate rectangular slabs of concrete 45 or similar material. Each slab is formed adjacent one side edge with a longitudinal groove 2, adapted to interlock with a longitudinal tongue 3 in the adjacent edge of an adjacent slab. These slabs interlocked in 50 this manner cooperate to form a pipe section which is of equilateral triangular cross sectional shape. It will be noted that while I do not limit myself to the exact shapes of the interlocking tongues and grooves, I prefer to use any interlock which permits of 55 each slab being identical in shape.

The ends of the slabs forming one pipe section are externally reduced or cut away, as indicated at 4, to conveniently accommodate the adjacent ends of the slabs of 60 an adjacent section, these last mentioned slabs being internally cut away as indicated at 5. Two adjacent sections of pipe are thus joined by the spigot joint above 65 described.

The pipes may be reinforced in any approved manner.

Although I have illustrated one of the preferred embodiments of my invention, it will be evident that various slight changes 70 and alterations might be made in the general form and arrangement of the parts described without departing from the invention, and hence I do not wish to limit myself to the precise details set forth, but 75 shall consider myself at liberty to make such slight changes and alterations as fairly fall within the spirit and scope of the appended claims.

I claim:

1. In a conduit section of the type including a plurality of identical interlocking wall members wherein each wall member near one side edge has an elongated tongue running parallel to said side edge and has 85

near the opposite side edge a groove running parallel to the last-mentioned side edge, such groove being adapted to take the tongue of a laterally adjoining wall member, the combination of three such wall 90 members for forming a conduit section, each wall member having plane parallel faces and having one of its side edges plane and perpendicular to the faces of said member and having its other side edge plane and 95 at an angle of 60° to said faces; whereby when three of said wall members are assembled with their tongues and grooves interfitting there is provided a conduit section 100

of uniform wall thickness and with an inner perimeter and an outer perimeter both defining a perfect and uninterrupted equilateral triangle, and whereby, for safety and compact arrangement in transportation and storage, a plurality of piles of the wall members may be arranged alongside each other and with the wall members of each pile in face to face contact and with the 105 60°-inclined side edge of each successive wall member in a pile reversely arranged 110 but vertically aligned and with the last-mentioned side edge of each wall member of

a pile and the same side edge of a wall member at the same level in an adjoining pile in face to face contact.

2. A triangular shaped conduit section, 5 consisting of three similar flat members, each member having adjacent one end on its inner face a V-shaped notch forming a tongue at the end of the member, and at the other end a notch of greater size than 10 the first notch, said notch leading out through the end of the member and extending inward from said end a distance approximately equal to the thickness of a

member and forming a longitudinal groove, the end of each member having a tongue 15 engaging the groove of an adjacent member, whereby the members will be firmly united, the sections will present a smooth outer surface so that the liability of the members being effected by the freezing and 20 thawing of the ground is reduced to a minimum and the members when disassembled can be packed in a comparatively small space for transportation.

J. OVILA MONTREUIL
